UNITED STATES PATENT OFFICE.

JAMES W. SNODGRASS, OF YOUNGSTOWN, OHIO.

DESIGN FOR A CHARM OR SIMILAR ARTICLE OF JEWELRY.

Application filed April 26, 1924. Serial No. 9,410. Term of patent 3½ years.

To all whom it may concern:

Be it known that I, JAMES W. SNODGRASS, a citizen of the United States of America, residing at Youngstown, in the county of Mahoning and State of Ohio, have invented a new, original, and ornamental Design for Charms or Similar Articles of Jewelry, of which the following is a specification, reference being had to the accompanying drawings, forming a part hereof.

The figure is an elevation view showing my new design for a charm.

I claim:—

The ornamental design for a charm or similar article of jewelry as shown.

J. W. SNODGRASS.
